UNITED STATES PATENT OFFICE.

HENRY H. CHARLES, OF MANOR TOWNSHIP, LANCASTER COUNTY, PENNSYLVANIA.

BROODER.

No. 892,650.

Specification of Letters Patent.

Patented July 7, 1908.

Application filed August 15, 1906. Serial No. 330,722.

To all whom it may concern:

Be it known that I, HENRY H. CHARLES, a citizen of the United States, residing in Manor township, in the county of Lancaster and State of Pennsylvania, have invented new and useful Improvements in Brooders, of which the following is a specification.

This invention relates to improvements in a brooder of that class in which a specially formed case of approved dimensions, being preferably twice as long as wide and of a depth equal to the width thereof, is internally provided with a lamp chamber, a heating tank, and a chick-chamber which is centrally and transversely divided into practically two equal parts by a depending hovering cloth which may be made of felt, the left hand part constituting the sleeping chamber and the right hand part the play or exercising ground.

The object of the invention is the production of a brooder, simple in construction, easily manipulated and not readily gotten out of order, being provided with certain novel features peculiar to itself, giving to this brooder a degree of preëminence over and beyond that of any other brooder now known to the trade.

The elements of the invention will severally and at large appear in the following description and they will be separately or combinedly set forth or pointed out in the appended claim or claims.

The purposes of the invention are attained by the mechanism, devices and means illustrated in the accompanying drawings with similar reference characters to designate like parts throughout the several views in which:—

Figure 1 is a perspective view of a brooder embodying the elements of the invention. Fig. 2 is a central longitudinal vertical section taken on the broken line $x-x$ in Fig. 1 with the near portion of the case in front of said line removed. Fig. 3 is a vertical cross section taken on the line $y-y$ in Fig. 2 and viewed from the right as indicated by the arrow 1. Fig. 4 is a vertical cross section taken on the line $z-z$ in Fig. 2 and viewed from the right as indicated by the arrow 2. Fig. 5 is a vertical cross section taken on the line $u-u$ in Fig. 2 and viewed from the left as indicated by the arrow 3. Fig. 6 is a top or plan view of the interior of the brooder with the upper portion of the front wall removed so as to show the true and false ventilating

holes in the upper edge thereof, and also showing the front end portion of the hover board removed. Fig. 7, is an end view of fender plate showing method of attaching to the heater tank C. Fig. 8, is a plan view of fender plate showing method of attaching to the heater tank C. Fig. 9, is an elevation of the fender plate showing method of attaching to the heater tank C.

In the drawing A designates the case of the brooder referred to in the opening paragraph hereto. The case A is preferably rectangular in plan and somewhat shed-like in form or external contour. At each of the four corners of the case is erected a post a , which posts are arranged in oppositely disposed pairs, supporting the front side wall a^1 , the rear side wall a^2 , the left end wall a^3 and the right end wall a^4 , which walls have their adjacent ends rigidly secured, in any approved manner, to the outer surfaces of said posts, while strips a^5 , covering said ends and rigidly secured in like manner, serve to provide a pleasing finish to the corners of the case. Said end wall a^3 , at the desired height above its lower end edge, is formed with a plurality of holes a^6 therethrough for the purpose of admitting air from the outside into the body of the case. Covering the case A is a shed-roof A^1 , centrally divided into two equal parts a^7 , each part covering one-half of the brooder case, having their central ends joined and supported by a downwardly and rearwardly inclined strip or bar A^2 with its extremities rigidly secured in any approved manner to near the top edges of the front and rear side walls a^1 a^2 , respectively, and said strip in its top surface is provided, lengthwise thereof, with a groove a^8 to drain any moisture that may percolate through the joint of said central ends, while the parts a^7 of said roof are preferably provided with a covering a^9 of approved sheet metal. And in the lower part of the case is a transversely placed brace strip or bar A^3 with its extremities also rigidly secured in any approved manner to the inner surfaces of said side walls a^1 a^2 , strengthening and stiffening said side walls.

In the lower part of the case A, which is bottomless, and extending throughout the entire length and width thereof, is the lamp chamber B, in which is arranged a suitable kerosene lamp or coal oil stove B¹ on a sliding base or board b, movable back and forth between guide strips b¹ and adapted to pass

through a door B^2 opening into said chamber and through the side wall a^1 , to the outer surface of which wall said door is suitably hinged. Between the left end corner posts 5 a^a , the inner surface of the wall a^3 is covered with a lining b^2 of any approved substance to prevent the penetration of moisture or chilling air therethrough. In the space between said posts a^a are horizontally disposed bars B^3 B^4 , engaging against the inner surface of said lining and their extremities abutting against the adjacent edges of said posts, B^3 being the lower bar and B^4 the upper one. To the inner edge of said bar B^3 10 is rigidly secured a strip or board B^5 of the required depth, adapted to receive the impact of the air entering through said holes a^6 , preventing fitful gusts thereof from contacting with said lamp B^1 and to deflect said air to and below the under edge of said board B^5 in its passage through the body of said lamp chamber, up to and out through a series of holes b^8 formed in the body of said end wall a^4 , the course of said air passage 15 being indicated by the arrows 4. And against the inner vertical edge of the bar B^4 is secured, in any approved manner, a board B^6 of approved dimensions, having formed therein an oblong slot b^4 , admitting heat into 20 the chick-chamber from the heating tank, both to be hereinafter described.

Above the lamp chamber B is arranged a tank C , of the required dimensions and of approved sheet metal. The tank extends practically over one-half of the area of the case, the left hand half, up to and against a suitable board C^1 , which extends over the right hand half, forming with another board C^2 , covering the tank, the floor or bottom of the 25 chick-housing chamber C^3 . And the tank comprises a bottom plate c and a top plate c^1 . In the bottom plate c , at the required point, is formed an oblong air inlet hole c^2 with its surrounding edge provided with a downwardly curved rim c^3 into which is fitted and secured as by soldering the specially formed upper end c^4 of an air induction tube C^4 , which tube is inclined downwardly through the lamp chamber B to the inner surface of 30 the front side wall a^1 , adjacent to the lower end edge thereof, where the lower end c^5 of the tube is passed through said side wall to the outer surface thereof and rigidly secured in place by means of a surrounding ring-flange C^5 , said end having been covered with a suitable screen c^6 to prevent the ingress of insects therethrough into the tank, fouling the same. The tank is formed with a left hand end c^7 , open throughout the entire 35 width thereof, which open end enters the space between said posts a^a , said bars B^3 B^4 and said lining b^2 to discharge the heated air from said tank into said space, in which is formed an air-tight flue or vent B^7 to conduct 40 said heated air upwards therethrough to said

oblong slot b^4 , through which slot said air is passed into said chick-housing chamber C^3 and distributed therethrough over the chicks, backs, providing the desired warmth, said air distribution being indicated by the arrows 5, while the slot b^4 is covered with a suitable screen b^5 to prevent the ingress of insects from annoying or disturbing the chicks. Within the tank, above the point where the flame of the lamp B^1 strikes the under surface of the bottom plate c of said tank, is arranged a shield or fender-plate C^6 , which latter plate is secured to the inner surface of said former plate c as by being riveted thereto, preventing the excessive heating 70 thereof. The left hand end of the plate c is integrally formed with a downwardly depending perpendicular flap or wing c^8 , having its lower end edge placed behind the upper end edge of said board B^5 to produce an air-tight joint therebetween, preventing fumes or gases from said lamp from passing therethrough and mixing with the heated air in its passage through said flue or vent B^7 and entering into the chicks' chamber C^3 . 80

Within the chicks' chamber, on top of the board C^2 is arranged a chicks' sleeping or warming chamber D , extending over the length and width of said board. At the required distance above the board C^2 is arranged a hover board D^1 , covering the same, and having arranged at the right hand end thereof a vertically disposed partition wall D^2 , against the inner surface of which said right hand end abuts. To the outer surface 90 of which partition wall, adjacent to the lower end edge thereof, is arranged a hover cloth D^3 , provided with vertical slits or cuts d , forming flaps or wings d^1 , for the passage of the chicks in either direction therethrough. 100 On the upper edge of said hover cloth is arranged a slat or strip d^2 , covering the same, the slat or strip being secured in place by headed nails or pins d^3 , and adjacent to the right hand end edge thereof is arranged a 110 board or strip D^4 , with its lower end edge resting on top of the floor board C^1 and secured to the inner surface of the rear side wall a^2 in any approved manner. A strip d^0 , with its lower end resting on the floor board C^1 , supports the forward end of the partition wall D^2 and it is arranged against the inner surface of the post d^5 , best shown in Figs. 3 and 6. The left hand end of said hover board D^1 is upheld by the top edge of said slotted board B^6 and the right hand end thereof is upheld by a slat or strip d^4 , which is secured in any approved manner to the lower end edge of said partition wall D^2 , which partition wall extends rearwardly to 120 the rear side wall a^2 , and the rear side of the hover board is upheld by a strip or board D^5 with its lower side edge rigidly secured to the top surface of the floor board C^1 and its left hand end is secured to the inner surface of the 125

130

slotted board B⁸, while the front side of the hover board is upheld by a strip D⁶, which is secured to the inner surface of the front side wall a¹ in any approved manner, as well as to a post d⁵ at its right hand end, which post is secured in place in any approved manner to the front side wall a¹, and to its upper end is secured the vertical front end edge of said partition wall D².

10 Said tank C, with its covering board C², and the right end floor board C¹ are upheld in position by longitudinal slats or strips C⁹, which are secured in any approved manner to the front and rear side walls a¹ and a² of the case.

15 In the front side wall a¹ of the case, adjacent to the upper end edge thereof, are formed a plurality of true and false ventilating holes, the false ventilating holes, extending half way through the body thereof, are designated by the reference character a¹⁰ and the true holes, extending the whole way through, by a¹¹, while the right end wall is provided with a hinged door A⁴ adapted to 20 open upwardly to give egress to the chicks from the housing chamber to the outside of the case and also to add to the ventilation, where an inclined embankment A⁵ forms a run-way, up and down which the chicks may 25 pass to and from the surrounding ground. In the front side wall a¹, and below said true and false ventilating holes is arranged an oblong panel A⁶ provided with transparent panes a¹², as of glass, for the transmission of light 30 into the chick-housing chamber C².

35 The several parts hereinbefore described and occupying the respective positions indicated in the drawings, an inspection thereof clearly shows. That the case being preferably twice as long as wide and of a depth equal to the width thereof and having no partition, other than the hover curtain through the middle, presents a large and roomy interior, making it easy to clean; that a kerosene 40 lamp or coal oil stove in the bottom of the case furnishes the required heat, dispensing with all heating drums in common use in the construction of most of other brooders now known to the trade; that above the lamp 45 chamber, which is at the bottom of the case, is situated a tank into which pure air flows from the outside of the case, and in flowing through the tank said air becomes heated, and flowing out through the left hand open 50 end thereof into the vent, thence upward through said vent to the oblong slot and therethrough into the chick-chamber; that the pure warm air having thus been introduced into the chick-chamber gradually 55 diffuses therethrough without any undue heating at any point; that said chick-chamber being large, the chicks can arrange themselves therein in any way so as to make themselves most comfortable; it will be noticed 60 that the hover cloth hanging centrally in

65 said chick-chamber, practically, but not actually, divides the chamber into two portions, the left hand end portion being the warmer and the right hand end portion the cooler; that by reason of the vertical slits in 70 said hover cloth the chicks can pass therethrough in either direction, when desiring more heat, they enter said warmer portion and when less heat, they enter said cooler portion and they may even pass through the 75 opening in the right end wall of the case into the open air; that the lamp chamber being large, prevents overheating of the oil in said lamp, thus avoiding danger of catching fire.

80 The invention having thus been ascertained and described and the manner in which its functions are performed, fully shown and set forth what is considered new and desired to be secured by Letters Patent is:—

85 1. In a brooder of the class described, in combination, a case comprising front, rear and end walls: end supporting posts at the intersection thereof: one of said end walls formed with inlet holes adjacent to the lower edge thereof: a detachable cover comprising two hinged halves resting upon the upper edges of the front, rear and end walls: a bottom secured within said walls: said walls and bottom forming a lamp chamber: a 90 door hinged to the outer surface of the front wall of said case: a sliding lamp board contained within said lamp chamber: supporting guide strips secured to the upper surface of the bottom of said lamp chamber within said 95 door: a heater tank secured to the upper surface of the case bottom: an induction tube having its upper end secured into said tank and extending through the front wall of said case near the lower edge thereof: a screen 100 covering the end of said induction tube: an impervious lining covering one of the end walls of said case and extending between the supporting posts of said case: a hover-board: 105 extending transversely across said case within and near the top thereof: a hover-cloth secured to the lower edge of said hover-board: the front wall of said case formed with air-inlet holes and an oblong transparent panel arranged below said holes: and a chick- 110 door hinged to the outer surface of one of the end walls of said case.

115 2. A brooder with a case comprising front, rear and end walls: end supporting posts at the intersection thereof: an impervious lining 120 covering one of said end walls: one of said walls formed with air-inlet holes extending through the body thereof and adjacent to the lower edge thereof: a bottom secured within said walls at a distance above the 125 ground: said walls and bottom form a lamp chamber: said end wall lining formed with a series of holes in the body thereof: a pair of horizontal bars secured to the inner surface of said end wall, one above and one below 130

said holes: fender boards secured to the inner surface of said lower bar so as to deflect the air through the body of said lamp chamber up and out through the holes in the body of said end wall.

3. A brooder with a case comprising front, rear and end walls: end supporting posts at the intersection thereof: one of said end walls formed with air-inlet holes adjacent to the lower edge thereof: an impervious lining covering one of said end walls: upper and lower horizontal bars secured to said end wall through said lining; said lower bar placed above said air-inlet holes: an air deflecting board secured to the inner surface of said

lower bar to deflect the air in its passage: the other end wall formed with a series of holes in the body thereof: a rectangular board secured to the vertical inner edge of said upper bar: and provided with an oblong slot, a screen covering said slot: a ventilating door hinged at its upper edge to the outer surface of said end wall: and an inclined plane erected underneath said door.

In testimony whereof I affix my signature, 25 in presence of two subscribing witnesses:

HENRY H. CHARLES.
